(57) **CLAIM**

The ornamental design for a tire as shown and described.

DESCRIPTION

FIG. 1 is a front elevational view of a tire showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front and right side perspective view thereof;

FIG. 8 is an enlarged view of portion 8 in FIG. 1;

FIG. 9 is an enlarged view of portion 9 in FIG. 3;

FIG. 10 is an enlarged view of portion 10 in FIG. 7;

FIG. 11 is an enlarged view of portion 11 in FIG. 7; and,

FIG. 12 is an enlarged view of portion 12 in FIG. 7.

The unevenly dashed broken lines illustrate the boundary of the enlarged views and form no part of the claimed design.
